(57) CLAIM

The ornamental design for a bracelet, as shown and described.

DESCRIPTION

FIG. 1 is a perspective view of a bracelet as seen from the top, and front showing my new design;

FIG. 2 is a top plan view thereof shown in an alternative environment;

FIG. 3 is a front elevational view of FIG. 2, the rear elevational view being a mirror image;

FIG. 4 is a right side elevational view of FIG. 2, the left side elevational view being a mirror image;

FIG. 5 is a bottom plan view of FIG. 2; and,

FIG. 6 is a perspective view thereof shown in an alternative environment.

All broken lines are for illustrative purposes only, and form no part of the claimed design.

1 Claim, 3 Drawing Sheets
